UNITED STATES PATENT OFFICE.

FRANK M. CONROY, OF CALDWELL, IDAHO.

MOLD FOR USE IN PRODUCTION OF FENCEPOSTS.

Application filed June 1, 1920. Serial No. 335,730.

To all whom it may concern:

Be it known that I, FRANK M. CONROY, a citizen of the United States, residing at Caldwell, in the county of Canyon and State 5 of Idaho, have invented certain new and useful Improvements in Molds for Use in Production of Fenceposts, of which the following is a specification, reference being had to the accompanying drawings.

10 This invention relates to certain improvements in molds and has relation more particularly to a device of this general character especially designed and adapted for use in the production of fence posts, or the like, 15 and it is an object of the invention to provide a novel and improved mold of a collapsible type and wherein means are provided for effectively maintaining the same in assembled relation and in a manner to withstand the pressure incident to the molding of the post, or the like.

Another object of the invention is to provide a novel and improved mold of this general character having means to permit 25 the proper application to the post of staple or other wire engaging elements.

An additional object of the invention is to provide a mold of this general character having novel and improved means whereby 30 the finished post or the like is provided with beveled or similar edges so that the post is free of sharp corners.

The invention consists in the details of construction and in the combination and arrangement of the several parts of my improved mold whereby certain important advantages are attained and the device rendered simpler, less expensive and otherwise more convenient and advantageous for use, 40 as will be hereinafter more fully set forth.

The novel features of my invention will hereinafter be definitely claimed.

In order that my invention may be the better understood, I will now proceed to 45 describe the same with reference to the accompanying drawings, wherein:

Figure 1 is a view in top plan of a mold constructed in accordance with an embodiment of my invention;

50 Figure 2 is a view in side elevation of the mold as herein disclosed with a portion broken away;

Figure 3 is a sectional view taken substantially on the line 3—3 of Figure 1;

55 Figure 4 is an enlarged fragmentary longi-

tudinal sectional view taken through one end portion of the mold;

Figure 5 is an enlarged transverse sectional view taken through a mold constructed in accordance with an embodiment 60 of my invention, one of the mold chambers having a molded block or post therein;

Figure 6 is a view in perspective of one of the wedge members herein employed; and

Figure 7 is a view in elevation of a post 65 produced with my improved mold.

As disclosed in the accompanying drawings, P denotes a pallet of requisite dimensions and preferably of wood and which has nailed, screwed, or otherwise secured to its 70 under face the transversely disposed strips or cleats 1 with adjacent cleats or strips 1 in relatively close proximity one to the other but spaced apart sufficient to prevent said cleats or strips from swelling tight together. These 75 cleats or strips 1 serve to prevent the pallet P from warping. Nailed or otherwise secured to the upper surface of the pallet P is a plurality of longitudinally spaced series of blocks 2 having their end portions beveled. Each series of blocks 2 is three in number and aligned transversely of the pallet P with the intermediate block substantially central of the pallet P and the end blocks 80 at a point in close proximity to the side 85 margins of the pallet.

The blocks 2 serve as abutments for the lower marginal portions of the side pieces or panels 3. As disclosed in the accompanying drawings, said side pieces or panels 3 are 90 four in number and each of which contacts with the inner face of a block 2 whereby provision is made for the molding of two posts. The panels or side pieces 3 are co-extensive in length but of a length less than 95 the length of the pallet P so that when the side pieces or panels 3 are applied the opposite end portions of the pallet P extends beyond the ends of said side members or panels.

End pieces or panels 4 coact with and 100 abut the opposite ends of the side pieces or panels 3 when applied and are interposed between said ends of the side pieces or panels 3 and the upstanding block 5, nailed 105 or otherwise secured to the upper surface of the pallet P. These blocks 5 coact with the lower marginal portions of the end pieces or panels 4 and the upper portion of each of said end pieces or panels has coacting 110

therewith a bracing member or strut 6, one end portion of which is adapted to seat in a longitudinally disposed recess 7 produced in the central portion of the upper part of 5 the coacting end piece or panel 4 while the opposite or lower end portion of said strut engages within a transversely disposed recess 8 positioned in the adjacent extended portion of the pallet P. The outer side 10 pieces or panels 3 have secured to the outer faces thereof the transversely disposed cleats 9 which operate to prevent the warping of said pieces or panels 3 and fitting between the inner side pieces or panels 3 are the 15 wedged members 10 which serve to maintain said intermediate or inner side pieces or panels 3 from springing outward during a molding operation. The upper surface of the pallet P within each of the mold 20 boxes or chambers afforded by adjacent side pieces or panels 3 is provided with a series of longitudinally spaced pockets or depressions 11, preferably cylindrical in form and positioned in accordance with the 25 requirements of practice. Screwed, or otherwise secured to the upper surface of the pallet P and overlying each of said pockets or depressions 11 is a metallic plate 12 provided with a pair of slots 14 preferably in parallelism and extending transversely of the pallet. Staples 15 or kindred elements 30 to be suitably imbedded within the molded post are inserted through said slots and extending upwardly from the pallet a distance 35 sufficient to permit the same to be effectively imbedded or engaged with the molded post. These staples 15, or kindred elements, provide means whereby wires, or the like, may 40 be readily secured or anchored to a completed post in the building of a fence structure.

Secured to the inner faces of each of the side pieces or panels 3 along the longitudinal margins thereof and co-extensive in 45 length with said side pieces or panels 3 are the strips 16 which may be of wood or metal and which are of such configuration in cross section to provide the finished or completed post with substantially beveled 50 edges so that said post is free of sharp corners or edges.

My improved mold is adapted for use in connection with a cementitious mixture and when said mixture is being applied within 55 the mold chambers, suitable reinforcing rods 17 are properly arranged therein so that the post, when formed, will possess a maximum of strength.

It is also of particular advantage to 60 provide means coacting with the upper marginal portions of adjacent side pieces or members 3 to hold the same against separating movement and, as herein disclosed, this is accomplished by the use of a plurality of 65 beams 18 adapted to be disposed trans-

versely of the mold at predetermined spaced points longitudinally thereof and to rest upon the upper edges of the side pieces or panels 3. An end portion of each of said beams 18 is provided with the depending 70 blocks 19 adapted to overlie and contact with the outer faces of the side pieces or panels 3 and with a central depending block 20 adapted to snugly fit between the intermediate or central side pieces or panels 3. 75

In view of the foregoing, it will be readily understood that my improved mold may be readily collapsed or disassembled when required and the parts therein can be readily applied when it is desired to perform a 80 molding operation. It is also to be understood that the side panels or pieces 3 are to be so arranged and of such dimensions as may be required in accordance with the character of post, or the like, to be produced. 85

From the foregoing description, it is thought to be obvious that a mold constructed in accordance with my invention is particularly well adapted for use by reason of the convenience and facility with which it 90 may be assembled and operated, and it will also be obvious that my invention is susceptible of some change and modification without departing from the principles and spirit thereof, and for this reason I do not wish to 95 be understood as limiting myself to the precise arrangement and formation of the several parts herein shown in carrying out my invention in practice except as herein-after claimed. 100

I claim:

1. A mold of the class described comprising a pallet, series of upstanding blocks carried by the pallet at longitudinally spaced points therealong, each of said series 105 comprising four blocks alined transversely of the pallet, side pieces adapted to be mounted upon the pallet and contact with the inner faces of the upstanding blocks, said side pieces being each of a length less 110 than the length of the pallet, whereby the opposite end portions of the pallet extend beyond the ends of the side pieces, end pieces adapted to be mounted on the pallet and about the ends of the side pieces, means 115 for holding said end pieces in applied position, cross members adapted to rest upon the upper edges of the side pieces, blocks depending from the extremities of each of the cross pieces for contact with the outer 120 faces of the outer side pieces, and a block depending from each of the cross pieces and substantially snugly fitting between the inner side pieces. 125

2. A mold of the class described comprising a pallet, series of upstanding blocks carried by the pallet at longitudinally spaced 130 points therealong, each of said series comprising four blocks alined transversely of the pallet, side pieces adapted to be mounted

upon the pallet and contact with the inner faces of the upstanding blocks, said side pieces being each of a length less than the length of the pallet, whereby the opposite 5 end portions of the pallet extend beyond the ends of the side pieces, end pieces adapted to be mounted on the pallet and about the ends of the side pieces, means for holding said end pieces in applied position, cross 10 members adapted to rest upon the upper edges of the side pieces, blocks depending from the extremities of each of the cross pieces for contact with the outer faces of the outer side pieces, a block depending 15 from each of the cross pieces and substantially snugly fitting between the inner side pieces, and wedge members insertable from above between the inner side pieces intermediate the cross members and engaging 20 the inner side pieces to further hold the same against movement one toward the other.

3. A mold of the class described comprising a pallet, series of upstanding blocks carried by the pallet at longitudinally spaced 25 points therealong, each of said series com-

prising four blocks alined transversely of the pallet, side pieces adapted to be mounted upon the pallet and contact with the inner faces of the upstanding blocks, said 30 side pieces being each of a length less than the length of the pallet, whereby the opposite end portions of the pallet extend beyond the ends of the side pieces, end pieces adapted 35 to be mounted on the pallet and about the ends of the side pieces, means for holding said end pieces in applied position, cross members adapted to rest upon the upper edges of the side pieces, blocks depending 40 from the extremities of each of the cross pieces for contact with the outer faces of the outer side pieces, a block depending from each of the cross pieces and substantially snugly fitting between the inner side pieces, the pallet being of wood, and cross 45 strips secured to the under face of the pallet and extending transversely thereof, adjacent cross strips being separated but in close proximity one to the other.

In testimony whereof I hereunto affix my signature.

FRANK M. CONROY.
